(74) Attorney, Agent, or Firm — Heidi Eisenhut; LOZA & LOZA, LLP

CLAIM

The ornamental design for an intake manifold as shown and described.

DESCRIPTION

FIG. 1 is a front, right, top perspective view of an intake manifold;

FIG. 2 is a rear, bottom perspective view thereof;

FIG. 3 is a right side thereof;

FIG. 4 is a left side thereof;

FIG. 5 is a front view thereof;

FIG. 6 is a back view thereof;

FIG. 7 is a top plan view thereof; and,

FIG. 8 is a bottom plan view thereof.

The broken lines show features of the intake manifold that form no part of the claimed design.

1 Claim, 8 Drawing Sheets
